UNITED STATES PATENT OFFICE

166,776

HOBBYHORSE OR SIMILAR ARTICLE

Darwin C. Stanley, Paramount, Calif.

Application October 4, 1951, Serial No. 16,837

Term of patent 14 years

(Cl. D34—15)

To all whom it may concern:

Be it known that I, Darwin C. Stanley, a citizen of the United States and residing at Paramount, county of Los Angeles, State of California, have invented a new, original, and ornamental Design for a Hobbyhorse or Similar Article, of which the following is a specification, reference being had to the accompanying drawing, forming part thereof.

In the drawing is illustrated a view in perspective of a hobbyhorse embodying my new design the opposite side of the device being similar.

I claim:

The ornamental design for a hobbyhorse or similar article, substantially as shown and described.

DARWIN C. STANLEY.
